CLAIM

The ornamental design for a hair removal device, as shown and described.

DESCRIPTION

FIG. 1 is a bottom perspective view of a hair removal device.

FIG. 2 is a top perspective view thereof.

FIG. 3 is a side perspective view thereof.

FIG. 4 is a bottom view thereof; and,

FIG. 5 is a top view thereof.

The broken lines are shown for illustrative purposes only and form no part of the claimed design.
